UNITED STATES PATENT OFFICE.

MAY BROOKS AND DERUELLE S. PORTER, OF WASHINGTON, DISTRICT OF COLUMBIA.

DESIGN FOR A MATCH-BOX AND STAMP-HOLDER.

SPECIFICATION forming part of Design No. 19,574, dated January 14, 1890.

Application filed September 18, 1889. Serial No. 324,360. Term of patent 7 years.

To all whom it may concern:

Be it known that we, MAY BROOKS and DERUELLE S. PORTER, citizens of the United States, residing at Washington, in the District of Columbia, have invented a new and original Design for a Match-Box and Stamp-Holder, of which the following is a specification, reference being had to the accompanying drawings, forming part thereof.

On the outer surface of the match-box E E are two flaps B B (shown in dotted lines in Fig. 1) in a parallel plane with the surface, which project from the side of the box, with a short curve at the upper and lower edges, respectively, as shown in Fig. 2.

A is a door or lid with a beveled surface, Fig. 1, provided with a clasp at C, forming a cover.

What we claim is—

The design for a match-box and stamp-holder herein shown and described.

MAY BROOKS.
DERUELLE S. PORTER.
